Filed June 14, 1965, Ser. No. 463,562
9 Claims. (Cl. 112—235)

ABSTRACT OF THE DISCLOSURE

Method and apparatus for accomplishing the result of moving material under the presser foot of a sewing machine by applying a fluid pressure onto the material from the presser foot, and simultaneously cooling the sewing needle with a jet stream.

This invention relates generally to sewing machines and more particularly to a method and apparatus for applying pressure from the presser foot to hold the cloth against the feed dogs or teeth of the machine to advance the cloth under the needle.

A primary object of this invention is to provide a method for permitting cloth to be advanced through a sewing machine that does not require the application of mechanical pressure to the cloth.

Another principal object is to provide a means for permitting cloth to be advanced through a sewing machine in such a way that no damage can be imparted to the cloth.

Another object is to provide a means whereby a presser foot may be constructed or an existing presser foot may be modified to permit the cloth to be advanced through a sewing machine without physical contact between the presser foot and the cloth.

A further object is to provide a method by which the medium of air may be utilized to provide the holding force to permit the cloth to be advanced by the feed dogs of a sewing machine.

An additional object is to provide an arrangement whereby compressed air is directed through a presser foot and against the cloth being worked to hold the cloth against the feed dogs of a sewing machine to that the cloth may be fed therethrough by the conventional feed mechanism.

And a still further object is to provide a presser foot for sewing machines that is similar to and interchangeable with a conventional presser foot but which includes provision for directing air through the foot and against the cloth being worked for the purpose described.

And yet another object is to provide a presser foot having a perforated bottom surface and means for directing pressurized air through the perforations to engage a cloth underneath.

And another object is to provide a presser foot mechanism wherein the interior of the presser foot is hollow and the bottom surface is perforated and wherein compressed air is directed into the hollow interior and out through the perforations when desired.

And still another object is to provide an arrangement whereby a standard presser foot may have a perforated air tube attached to its bottom surface and may have a perforated shoe attached to the air tube in such a way that compressed air may flow through the tube and out through the perforations in the shoe for the purpose disclosed.

And an object of this invention is to provide a means whereby differential pressure between the top of the cloth being worked and the bottom of the cloth permits the cloth to be advanced through a sewing machine by conventional means.

2

An object is also to accomplish the function of a presser foot without the use of spring pressure.

Another object is to provide a means in a presser foot structure to provide an air cushion between the foot and the cloth to reduce friction therebetween.

An additional object is to provide a needle coolant and a means for delivering the coolant to the needle in operation.

These and other objects and advantages will be apparent from an examination of the following specification and drawing in which:

FIGURE 1 represents a side elevational view of the presser foot assembly apparatus of this invention.

FIGURE 2 is a front elevational view of the device of FIGURE 1.

FIGURE 3 is a bottom plan view of the device of FIGURES 1 and 2.

FIGURE 4 is an elevational cross sectional view of the device of FIGURE 1 installed and operating, showing a cloth being sewn in the practice of this invention.

FIGURE 5 is a side elevational view of another embodiment of the device of FIGURE 1.

Referring now more particularly to the characters of reference on the drawing it will be observed that the 25 presser foot apparatus of this invention indicated generally at 2 consists basically of a vertical shank 3 to which is pivoted at 4 a horizontally extending foot member 5, and in contradistinction to conventional presser feet, a rearwardly extending fluid conduit 6.

30 Examining the individual parts in closer detail in FIGURES 1 and 5 it is seen that the shank 3 includes a vertical channel 7 on one side and a relatively short vertical slot 8 on the opposite side, both configurations being included to permit this conventional shank to fit 35 a standard industrial sewing machine. The lower end of the shank 3 is reduced to a small neck at 9 and is enlarged again at 10 to receive pivot pin 4 through an opening 11 (FIG. 4). The lower rear of enlarged area 10 includes a recess 12 which retains a coil spring 13, also shown in 40 FIGURE 4.

The foot 5 is similar in external appearance to a conventional presser foot, but the foot 5 of this invention includes an enlarged internal cavity 14 that extends from the rearmost section of the body of the foot out into a 45 portion of the two forwardly extending toes 15, as seen in FIGURES 3 and 4. The bottom surface of foot 5 includes a plurality of openings 16 that connect the internal cavity 14 with the outside surface. And the facing vertical sides of the toes 15 include horizontal openings 17 50 for a purpose to be described hereafter.

The fluid conduit 6 is physically connected to and integral with the foot 5, and the hollow interior 18 of the conduit is in communication with the cavity 14. This construction permits a flexible air hose (not shown) to be 55 connected to conduit 6 via fitting 20 and permits air or other fluid to be selectively introduced through conduit 6 and into cavity 14 under pressure by means of well known apparatus. When the medium (air or other fluid) arrives in cavity 14 under pressure it immediately passes 60 through the openings 16 and 17 at a reduced but substantial pressure and at an increased velocity.

In operation the entire presser foot apparatus 2, being 65 installed on an otherwise conventional industrial sewing machine, is lowered in the usual manner to the vicinity of the cloth or other material to be sewn. However in this operation the bottom surface of foot 5 does not ordinarily touch the material, indicated at 21 and 22 in FIGURE 4. But rather the material 21 and 22 is resting one on the other and both overlying a sewing machine plate 23.

70 Sewing machines of this type are equipped with feed dogs or jaws 24 which reciprocate in an opening such as 25

in plate 23 to advance the material 21 and 22 through the machine and past the needle, indicated at 26. However in conventional machines the advance of cloth is achieved by the physical pressure of the bottom of the presser foot against the top of the material on one side and by the grip of the feed dogs on the other side. The grip of the dogs is maintained throughout the stroke of the dogs by virtue of the physical pressure asserted by the presser foot. There is a tendency however when opposing physical pressures are exerted on a material and where one of the forces is applied through sharp or abrupt teeth for the material to be damaged. This tendency is eliminated in the present invention by the use of a fluid pressure to provide the backup needed to permit the feed dogs to carry out their normal function.

The desired fluid pressure is applied when needed by well known fluid control apparatus (not shown). For example after the layers of material to be sewn have been laid over the plate and under the needle, and after the foot has been lowered to the vicinity of, but not necessarily touching the material, the fluid, preferably air, is directed under pressure through the tube interior 18 and into cavity 14 from whence it passes out through openings 16 to apply sufficient pressure to the top side of material 21 to create a pressurized area between the material and the foot as indicated at 27. The feed dogs 24 are thus able to function to advance both materials 21 and 22 through the machine without requiring any direct physical contact by the foot against the material.

The pressurized medium performs another valuable function in this invention also. In sewing at high speeds on heavy materials the sewing machine needle heats up to a temperature that both shortens the life of the needle and makes it more subject to breakage than an ordinary needle at room temperature. This detrimental heating has been substantially reduced by the employment of the small orifice horizontal openings 17 which direct a high velocity air stream or jet onto the needle while it is operating.

In the embodiment shown in FIGURE 5, a conventional presser foot F has been modified in such a manner to permit the achievement of the desired results of this invention. The foot F is attached at its underside to the flattened end 30 of a fluid conduit 6A. A perforated shoe 31 is then attached to the underside of the flattened end 30. A series of perforations in the flattened section 30 are aligned with the perforations in the shoe 31, so that pressurized fluid in conduit 6A will pass out through both sets of perforations and will hold the material down against the feed dogs 24. Laterally projecting holes 17A may be drilled in the flattened section 30 before it is installed onto presser foot F.

It will be observed that the foregoing description and drawing have disclosed a unique and novel presser foot apparatus which will provide the advantages enumerated but without the inherent disadvantages of conventional presser foot arrangements. It is understood that changes may be made which come within the spirit of this invention and all such changes or modifications are considered to fall within the scope of the appended claims.

What is claimed is:

1. A method for sewing material, comprising in combination the steps of: directing pressurized air through perforations in the bottom of a sewing machine presser foot and against the material in such a manner as to hold the material in place, advancing the material through a sewing machine, and simultaneously directing a coolant air in a high velocity flow against the sewing machine needle.
2. In a sewing machine, a presser foot apparatus including a presser foot, means for advancing material through said machine, said presser foot including a hollow interior and including at least one opening that is small relative to the dimensions of said foot between said interior and the bottom of said foot, and means for directing pressurized air through said hollow interior and out through said bottom opening, and wherein said at least one opening comprises a series of perforations.
3. In a sewing machine, a presser foot apparatus including a presser foot, a means for advancing material to be sewn through said machine, and means attached to said presser foot for applying fluid under pressure between the entire presser foot and material in such a manner that no part of the foot rests on the material.
25. 4. An apparatus as in claim 3 wherein said fluid is compressed air.
5. In a sewing machine, a presser foot apparatus including a presser foot having projecting toes, a conduit attached to said foot, said foot defining at least one side opening in said toes and including a bottom defining at least one opening therein, said foot structure defining a hollow interior and said presser foot apparatus defining a continuous hollow internal path through said conduit, through said interior, through said side opening and 35 through said bottom opening.
6. In a presser foot apparatus, a presser foot, a separate conduit member attached to the underside of said presser foot and a shoe member attached to the underside of said conduit.
40. 7. In a presser foot apparatus, a presser foot, a conduit member having at least one opening physically attached to the underside of said foot, and a shoe member having at least one opening attached to the bottom of said conduit.
45. 8. A presser foot apparatus as in claim 7 wherein each said at least one opening comprises a series of coincident perforations.
9. A presser foot apparatus as in claim 7 wherein one said at least one opening in said conduit member is generally horizontal.
